REGISTER APPARATUS FOR PRODUCING
MANIFOLDED BUSINESS RECORDS

William Dale Winders, Columbus, Ohio

Application November 27, 1950, Serial No. 197,739

6 Claims. (Cl. 282—5)

1

This invention relates to an improved register or record-manifolding appliance of the type employed in making and keeping records of various business transactions. More particularly, the present invention provides a register constituting an improvement in the apparatus set forth in my prior Patent No. 2,269,067, dated January 6, 1942.

The present invention has for an object to provide an improved entry-manifolding register employing a movable impression-transferring web carried by and extending between removable rolls mounted in the ends of the register, and wherein provision is made for bringing into registry with the web and each other a pair of separable record-receiving sheets, one of the sheets being placed above the web and held in desired registration with a second sheet placed beneath the web, whereby inscriptions applied to the top sheet or record are simultaneously applied to the web and underlying sheet or sheets.

It is another object of the invention to provide an improved means in a register of this character for locking the impression-transferring web within the confines of the machine, so that while the web is retained in the machine, inscriptions applied thereto can not, without detection, be altered or varied from the inscriptions or markings applied thereto from a superposed and removable record-receiving sheet.

It is another object of the invention to provide a register or accounting machine of this nature in which the roll-mounted and impression-receiving and transmitting web is supported within the confines of the outer casing of the machine in a sliding drawer, the latter being held normally against movement by a key-actuated lock mechanism, so that when the drawer is released, the same may be moved to an open position, outside the limits of the casing, in which the web and its associated rolls will be readily available and conveniently accessible for removal and replacement.

A further object of the invention is to provide an improved manually controlled key-actuated means in a machine of the character set forth for effecting the winding and unwinding of an impression-receiving and transmitting web on and from revoluble rolls, the latter being supported in spaced longitudinal relationship in a sliding frame drawer formed with guides through which is passed in a flat elongated form the intermediate length of the web, the drawer carrying at the top thereof a horizontal table over which the elongated intermediate portion of the web is advanced.

2

A further object is to provide means in association with the table of such a machine for rotatably holding in association with a carbon web removable top and bottom record-receiving sheets, whereby inscriptions made on the top sheet will be transmitted to the web to produce a corresponding record on the latter, and then transmitted by the web to the bottom record sheet, producing thereby three duplicative independent records simultaneously with the making of a record inscription on the top sheet.

It is a further object of the invention to provide improved means for holding removable top and bottom record-receiving sheets on each side of an impression-imparting web or ribbon, so that at the time a record-inscription is being made on an exposed record sheet, the three normally separated record-receiving members will be held together in definite relationship, enabling inscriptions applied to the first or top sheet to be legibly transmitted to two or more underlying sheets.

Still a further object of the invention is to provide an account-maintaining machine of the character set forth in which ruled record sheets or cards having definite entry-receiving spaces or boxes are provided, and wherein provision is made in the construction of the machine for accurately registering the spaces or boxes on a record sheet positioned under an impression-transmitting web with desired entry-receiving spaces or boxes present on an upper sheet.

The present invention further aims to improve record-keeping apparatus of the character set forth by simplifying the mechanical construction thereof, rendering such appliances more positive in their mechanical operation and convenient to employ, to provide greater protection for the record-receiving sheets, webs or cards employed in connection therewith by preventing tampering or other unauthorized manipulation therewith, and to improve generally apparatus of this character.

For a further understanding of the invention, reference is to be had to the following description and the accompanying drawings, wherein:

Fig. 1 is a perspective view of a record-manifolding register formed in accordance with the present invention;

Fig. 2 is a vertical transverse sectional view taken through the register on the plane indicated by the line II—II of Fig. 1;

Fig. 3 is a vertical longitudinal sectional view taken through the register on the line III—III of Fig. 1;

Fig. 4 is a detail vertical longitudinal sec-

tional view on the line IV—IV of Fig. 1, the scale of the figure being greater than that of Fig. 3;

Fig. 5 is a transverse sectional view taken through the register and disclosing the roll upon which the carbon record-receiving and transmitting web is wound in the operation of the machine. In this figure there is also disclosed the manually operated key for rotating the web-winding roll;

Fig. 6 is a vertical traverse sectional view on the line VI—VI of Fig. 5;

Fig. 7 is a similar view on the line VII—VII of Fig. 5;

Fig. 8 is a detail perspective view of the roll-winding key;

Fig. 9 is a plan view of the upper record sheet or card used in connection with the register of the present invention;

Fig. 10 is a similar view of the lower record-receiving sheet or card used in association with the register of the present invention and over which the carbon impression-transmitting web is passed;

Fig. 11 is a detail plan view disclosing on a larger scale the latch held apertured hinge plate utilized in the present invention for holding record sheets in manifolding relationship.

The present invention provides a mechanical aid in the keeping of accurate records in fiscal systems of the type in which customers of business concerns are provided with an account record, usually in the form of a book, sheet or card, while the management of such a concern retains a record in the form of a ledger sheet or card for each customer, the entries on which corresponding with those made on the customer's account sheet or card. When a customer makes a purchase or payment, the two record sheets or cards are adapted to be placed in adjacent relationship with a web of carbon paper or the like placed between them, so that an entry made on a card or sheet occupying an uppermost position will be transmitted to the carbon web and thence to the underlying sheet or card. In this system three records are made simultaneously: first, the entry on the customer's sheet; second, an entry on an impression-receiving and transmitting carbon-type webbing, and, third, a webbing-transmitted impression on the underlying management-retained ledger card or sheet.

In carrying out this system, the impression-receiving and transmitting webbing involves a pair of superposed carbon paper strips, one strip being placed above the other in registering but separable relationship, so that an impression imparted to the upper strip of the webbing, as by marking on a superposed record sheet or card, will be transmitted and inscribed on the upper surface of the under strip of the webbing. In addition, the said under strip serves to transmit the same impression to a ledger card or sheet placed in the machine beneath the webbing.

In accordance with the present invention, the customer's sheet or card is retained by the customer and presented at intervals to the management of a business concern for the purpose of having business-recording entries made thereon. The complementary ledger card retained by the management is also individually filed, but is withdrawn from its file by the management upon presentation by the customer of his card or sheet for entry-making purposes. The two cards or sheets are then placed in the register of the present invention, with the customer's card or sheet

overlying the management's ledger card or sheet, and the carbon webbing arranged between the same, whereby to reduce simultaneously the manifold and records above described.

Further, the present invention provides a register in which the carbon webbing, composed of the two adjoining carbon strips, each of which having the inscription-transferring material coated on its under surface, is retained in a locked manner in the confines of the machine, so that the record afforded by the carbon webbing may be removed from the machine by an authorized or key-provided person and analyzed for information independently of the entries appearing on the management retained ledger card or cards, whereby a daily receipts record is produced by the notations on the carbon webbing, which may be readily totaled at the end of a given business period.

Further, the present invention provides a register which is convenient to use in carrying out the above-described system of account keeping. In this regard, the machine embodies an outer casing in which is slidably mounted an associated drawer member, web-receiving rolls being rotatably supported in the opposite ends of the drawer member, the rolls receiving the ends of the carbon paper webbing, so that a length of the webbing, existing between the rolls, may be presented to the top of the machine for insertion between the customer's and management's account cards, the top of the machine involving an improved pocket structure by which tampering with the records produced by the machine is rendered difficult or impossible and wherein provision is made for adjusting the lower account card received within the pocket relative to the upper or customer's card, so that entries may be made on the proper space or spaces adapted for receiving the same on the under or ledger card.

The register comprises, in one of its preferred embodiments, an outer boxing or casing 15 which embodies vertical, longitudinally extending, parallel side walls 16—16, end walls 17 and 18, a horizontally disposed top wall 19 and horizontal bottom flanges 20, the latter being turned inwardly and laterally, in this instance, from the lower edges of the side wall 16 and the end wall 17. The end wall 18 is preferably in the form of a door, the same being hinged to one end of the top wall 19 as at 21, while the lower or free end of the door carries desirably a key-actuated lock 22, the movable keeper 23 of which, as shown in Fig. 3 and when actively positioned, holds the door against unauthorized opening movement.

Internally, the boxing or casing is braced by vertical transversely extending rigid partition members 24. The top wall 19 may be provided along its outer edges with depending flanges 25, which are adapted to be suitably fastened to the upper edge portions of the side walls 16 and, also, the front wall 17. Forming a stationary component part of the boxing or casing 15 are internally positioned spaced longitudinally extending guide strips 26 and 27, these strips being carried in connection with the outer side wall 16 and the upper ends of the partition members 24, as indicated in Fig. 2.

Mounted for sliding movement in the boxing or casing 15 is a web-receiving drawer 28. The drawer embodies vertically disposed, longitudinally extending, parallel and transversely spaced side plates 29—29. These plates are united at their ends by transversely extending rigidly joined partitions 30 which, in association with the side plates 29—29, provide in the opposite

ends of the drawer roll-receiving chambers 31 and 32. The side plates 29 and the partitions 30 also effect the support, and have rigidly associated therewith, a horizontally disposed base panel 33. This panel is formed marginally with upstanding flanges indicated at 34 to which are welded, or otherwise secured, to the under surfaces of a longitudinally extending drawer plate 35, the latter having its outer longitudinal edges supported for sliding movement in guide slots 36 provided longitudinally in the casing of the register by spaces formed between the upper surfaces of the strips 26 and the under surfaces of the top wall 19.

It will be noted that the inner longitudinal edges of the runner members 35 are disposed above and in spaced relation to the upper surfaces of the horizontal panel member 33 of the drawer, so that a space is provided between these parts between which a removable bottom record-receiving sheet or card 37 is adapted to be placed, with the card resting on the upper surface of the panel member 33.

The card 37 is inserted from the right side of the machine, as the latter is viewed in Fig. 1. In this respect, the right longitudinal edge of the top wall 19 is longitudinally recessed as at 38, thereby forming the entrance portion of a card-receiving pocket P in which the sheet or card 37 is positioned horizontally for both lateral and longitudinal adjustment. The guide strip 27 provides a horizontal ledge 39 on the right side of the machine on which the outer portion of the card 37 rests, the remainder of the card resting when in the pocket on the panel member 33. In registration with the ledge 39, the panel 33 is formed with a downturned lip 40, so that when the card 37 is inserted into the pocket, after the card passes over the ledge 39, the lip 40 will serve to guide the same into engagement with the upper surface of the panel 33, for lateral advancement over the top of said panel and until the opposite longitudinal edge of the card 37 engages with the upstanding movement-limiting flange 34, shown at the left of Fig. 2.

Rotatably mounted in the roll chamber 31 is a roll or spool 41. To the tubular axial core of this roll or spool there is secured one end of an impression-receiving and transmitting composite web 42, the web being wrapped spirally around the roll or spool, as shown in Fig. 3. The composite web comprises a pair of paper strips disposed in registering superposed relationship. The upper of these strips, indicated at 42a, has its upper surface coated with a carbon or similar impression-transferring medium, and the lower strip 42b is similarly formed, except that the upper surface of the lower strip preferably possesses a light coloration, so that the same may constitute a record, the latter being produced by the carbon or like coating applied to the under surface of the upper strip 42a, and which is in intimate contact with the top record-receiving surface of the lower strip 42b. These strips are handled as a unit, that is, as a single ribbon when the same are in the machine, but upon the removal of the webbing from the machine, the strips may be separated, the upper strip being discarded, if desired, while the lower strip is retained for the data present on the upper surface thereof.

From the roll or spool 41, the composite web 42 is advanced over a stationary wall 43 located in the chamber 31, and with which wall the web is maintained in frictional contact by a spring-pressed hingedly movable bar 44. After being

trained between the wall 43 and the bar 44, the web is directed angularly upwardly and its longitudinal marginal edges are received in guide channels 45. These channels are formed between the inner longitudinal edges of the runner members 35 and the under surfaces of the top wall 19 of the outer casing, as disclosed more particularly in Fig. 2. The intermediate portion of the web is thus disposed in a substantially horizontal plane, and passed immediately beneath the top wall 19 and above the top panel 33 of the drawer 28, the under surfaces of the web being disposed above the top surface of the wall 33 so that the pocket P for the reception of the ledger card 37 is formed in the top of the machine. This pocket possesses a considerably greater length than the card 37, so that the latter may be adjusted longitudinally in the pocket to bring the entry-receiving boxes or spaces thereon into vertical registry with those appearing on a customer's record card or sheet 46, shown in detail in Fig. 9 of the drawings. The merchant's ledger card 37 possesses a greater width than the customer's record card or sheet, as will be observed by comparing Figs. 9 and 10. The wider ledger card 37 projects outwardly through the open side 38 of the pocket, where its outer edge may be grasped for manipulation.

Preferably, the ledger card 37 bears at the top thereof spaces 47 in which to enter the name and address of the customer and also the assigned number which the account of the customer bears. Similar spaces and account numbers appear at 48 at the top of the customer's card 46.

Beneath the heading on each of these cards, there appears spaced parallel horizontally extending ruled lines 49, which are intersected by spaced parallel vertically extending column-forming lines 50, the lines 49 and 50 producing columns of boxes 51 for appropriate entries on these record cards or sheets. For example, the dates of various business transactions, charges made against the customer, credits or payments made by the customer and the balance of a given account following the entry of said credits or debits. As shown at the right of Fig. 10, a column is provided allowing for the consecutive numbering of each of the boxes or spaces appearing between the horizontal lines 49. In Fig. 10, this column of consecutive numbers is indicated at 52, and is disposed at the extreme right of the ledger card 37, whereas the corresponding column of numbers 53 of the customer's card or sheet is disclosed at the left thereof. These numbered columns are provided for convenience in effecting the registration of said spaces or boxes on the ledger card with those on the customer's card.

To hold the customer's card in place while an entry is being made thereon, I use a hinge cover plate 54, which is of rectangular formation and the length of which is but a fractional part of that of the outer casing of the machine as shown in Fig. 1. In this instance, the plate 54 is hinged as at 55 in connection with a stationary base leaf 56 of the hinge which is fastened to the upper surface of the top wall 19. A coil spring 57 may surround the pintle of the hinge 55 for the purpose of moving the cover plate normally in an upward direction with respect to the upper surface of the top wall 19. A spring-pressed latch 58, slidably mounted in a housing 59 is also mounted on the top 19 to lock or hold the cover plate in its down position. When the latch is released from engagement with the edge of the cover plate, the latter moves upwardly under the influence of the spring 57, so that the customer's

card 48 may be placed on the top of the machine in an applied operative position, or removed from said position.

The cover plate is formed to include an inscription-admitting opening 60 and plate 35 with a registering opening 60a, so that appropriate entries may be made on the proper spaces allotted therefor on the customer's card, and, through the carbon webbing, transmitted simultaneously to the lower record strip of such webbing and the ledger card 37. At the left of the opening or slot 60, there is provided an aperture 61 in the cover plate which is adapted to register with one of the numbers provided in the vertical column of figures 53 shown at the left of the card 37 in Fig. 9, whereby to designate to the bookkeeper or teller which of the horizontal spaces of the ledger card is in registry for entry-receiving purposes with the opening 60.

Similarly, the base leaf 56 of the cover plate hinge, the top plate 19 of the outer casing, and the guide strip 26, shown at the right of Fig. 2, are formed with vertically registering eight openings or apertures 62. The apertures 62 are adapted to register vertically with any one figure appearing in the column 52 of Fig. 10, so that the bookkeeper or teller will by noting the number on the card 37 in registry with the apertures 62 be enabled to determine immediately the box or space on the card 37 which will receive the entry inscription. Due to the length of the pocket P, the card 37 may be adjusted in said pocket to bring a desired space on the ledger card into registry with the opening or aperture 62.

In the roll chamber 32 of the drawer member 28, there is provided a winding spool or roll 63. The latter is adapted to receive the outer or free end of the carbon paper webbing 42 which is wound thereabout as it is withdrawn from the roll or spool 41, the webbing being advanced longitudinally a limited distance for each entry made on the account sheets 37 and 48, enabling a clear and legible record to appear on the upper surface of the lower strip member 42b of the webbing.

To effect rotation of the roll or spool 63, I find it advantageous in the interests of mechanical simplicity to do so through the operation of a manually rotated key shown at 64. This key is formed to provide a stem having a cylindrical hub 65 on the outer end of which a finger-engaging bar 66 is carried to rotate the stem, the bar 66 being disposed exteriorly of the machine casing, as shown in Figs. 1 and 5. In the latter figure of the drawings, it will be observed that the stem of the key, adjacent its cylindrical hub 65, is formed with an annular groove 67 and a section 68 which is square or polygonal in transverse cross section. By the squared region 68, the stem is formed with a diametrically reduced cylindrical section 69, which passes through an opening 70 formed in one of the side walls 29 of the drawer member, so that the extension may be positioned in a telescoping manner within one end of the tubular longitudinally extending core 71 of the roll or spool 63, as shown more particularly in Figs. 5 and 7. The core 71 is additionally supported by means of an elongated cylindrical stud 72 which projects stationarily from a wall 29 of the drawer member disposed opposite to that through which the extension 69 projects, the extension 69 when operatively positioned, as in-

dicated in Fig. 5, being arranged in longitudinal alignment with the stud 72.

To unite the free end of the carbon webbing with the core 71, the latter is formed on its outer surface with a longitudinally extending groove 73, in which the free end of the carbon webbing is positioned and locked. Such locking is produced by providing the stem of the key 64 with an elongated finger 74, which enters the groove 73 and resiliently presses on the free end of the carbon webbing to hold the same securely against accidental displacement in said groove, and so that by rotating the key, corresponding rotation will be imparted to the hub or spool 63, and the carbon webbing wrapped thereabout.

To hold the webbing against return movement, there is mounted on the squared section 68 of the key 64 the elongated hub 75 of a ratchet wheel 76, the hub 75 being provided with a squared or polygonal socket to receive the key section 68 and rotate in unison with the latter. The peripheral teeth of the ratchet wheel 76 cooperate with a spring-pressed pawl 77 which is pivotally mounted on the outer end of a pin 79 projecting stationarily in a horizontal and inward direction from a tubular bearing sleeve 80 which is carried by one of the casing walls 13. In this instance, the sleeve 80 is formed with an opening 81 through which projects the depending nose 82 of a detent 83. This detent is pivotally mounted as at 84 on the partition 30 and is spring-pressed as at 85 so that the nose end 82 thereof will be received in the annular groove 67 of the key 64 when the latter is operatively positioned in the machine, as disclosed more particularly in Figs. 5 and 6. With the nose 82 in the key groove 67, the key will be locked against accidental withdrawal from the machine. However, when the end door 18 of the casing is opened by key actuation of the lock 22, the detent will be accessible, so that it may be manually raised, released from engagement with the groove 67 and the key removed, facilitating the operation of removing and replacing the carbon webbing.

In order to maintain the webbing and the cards 37 and 48 in relatively close engagement with each other, at the time an entry is made on the uppermost record, the table-forming panel 43 of the drawer in registry with the slot or inscription-receiving opening 60, when the drawer is actively positioned in the casing, is formed with a raised region 86, as shown more particularly in Figs. 2 and 4. The raised region 86 elevates the card 37 correspondingly, bringing the same closer to the under surface of the lower strip of the carbon paper webbing. Similarly, the marginal edges bounding the opening 60 of the cover plate are inwardly and downwardly curved, as indicated at 87, so that when the cover plate is in its lower position, and retained by the latch 58 on the top of a record card 46, the latter is locally depressed so that it is held in relatively close relationship with the upper surface of the top strip of the webbing 42, assuring the application of the entry inscribed on the top sheet to the webbing and the lower record card.

I claim:

1. In a manifolding register; a casing formed with a horizontal top wall having an inscription-producing opening formed therein; a carbon paper-carrying frame removably positioned in said casing; spooling devices removably and rotatably supported in longitudinally spaced relation in the ends of said frame, said devices hold-

ing a record-receiving and inscription-transferring carbon paper webbing, rotation of said devices serving to move said webbing under the opening in the top wall of said casing; guide means, including a table plate, carried by said frame and along which the webbing is advanced longitudinally and horizontally when being passed from one of said spooling devices to the other; a base panel arranged below said guide means and forming a part of said frame, said base panel being spaced from said guide means and table plate to form a pocket in the frame which opens to one side of said casing; a movable clamping plate carried by the top of said casing, said clamping plate serving to maintain a record member removably positioned between the same and the top wall of said casing in a fixed position, whereby to enable an entry inscription applied to said record member to be manifolded on the juxtaposed webbing and a record sheet occupying said pocket; and manually operated means accessible from the exterior of said casing and removable therefrom for rotating one of said spooling devices and imparting longitudinal movement to the webbing connected therewith.

2. In a manifolding register; a casing; a carbon paper carrier removably positioned in said casing; means for rotatably supporting a transfer paper-carrying spool in said carrier, said last-named means including a key formed with a shank having a squared region, an annular groove, and a spool-engaging extension; a bearing member formed with a wall of said casing; a ratchet wheel rotatably supported by said bearing member, said wheel having a hub formed with an opening for the reception of the squared region of said key shank; a pawl engageable with teeth provided on said ratchet limiting the key for rotation in but a single direction; a detent carried by said casing and engagement with the groove of said shank to hold said key against longitudinal displacement; and a tongue carried by the spool-engaging extension of said shank rotatably uniting said key with said spool and transfer paper arranged thereon.

3. In a manifolding register, an elongated casing embodying top, side, end and bottom walls, there being a drawer-receiving opening in one of said end walls and an inscription opening formed in and disposed intermediately of said top wall, record-holding plate means hingedly mounted on the top wall of said casing, said plate means being formed to provide a restricted inscription slot adapted for registry with said inscription opening in said top plate, a drawer slidably positioned in said casing, said drawer including spaced base and table panels arranged adjacent to and in parallel relationship with the top wall of said casing immediately beneath the same, said table panel being formed with an opening intermediately of the length thereof arranged in vertical registry with the opening in said top wall and the slot of said plate means, said base and table panels being spaced to produce an open-sided pocket for the removable reception of a record sheet and the adjustment of said sheet relative to said inscription openings, spooling devices removably and rotatably supported in the opposite ends of said drawer, said devices holding a record-receiving and inscription-transferring webbing, the intermediate portion of which being movable over said table panel and below the top wall of said casing, and means accessible from the exterior of said casing for imparting move-

ment to said spooling devices and the webbing carried thereby.

4. In a manifolding register, an elongated casing having a top wall and a movable door-forming end wall, a drawer slidably positioned in said casing and movable into and out of the latter through the end of the casing containing said door, the top of said casing intermediately of the length thereof being formed with an inscription opening, said drawer being formed to embody a guide plate arranged when the drawer is operatively positioned within the casing immediately below and in parallel relationship with the top wall of said casing, spooling devices carried by the ends of said drawer, said devices holding a record-receiving and inscription-transferring webbing with the intermediate portion of the webbing extending over said guide plate and beneath the top wall of said casing in registry with said inscription opening, a base plate formed with said drawer immediately beneath said guide plate and spaced from the latter to provide a pocket for the reception of a removable lower record sheet, said base plate being formed intermediately of its length with a locally raised region projecting above the horizontal plane in which the major portion of the base plate lies, said locally raised region being disposed in registry with the inscription opening in said top wall and said guide plate, means carried by the top wall of said casing for removably clamping an upper record sheet in desired registry with said inscription opening, and manually operated means accessible from the exterior of said casing for operating said spooling devices to impart longitudinal movement to said webbing.
5. In a manifolding register, an elongated casing embodying top, side, end and bottom walls, there being a drawer-receiving opening in one of said end walls and an inscription opening formed in and disposed intermediately of said top wall, a drawer slidably positioned in said casing and inserted through said drawer-receiving opening, said drawer at the top thereof including spaced lower and upper horizontal panels arranged adjacent to and in parallel relationship with the top wall of said casing immediately beneath the same, said upper panel being formed with an opening intermediately of its length arranged for vertical registration with the opening in said casing top wall, said lower and upper panels being relatively spaced to produce an open-sided pocket between the same, the open side of the pocket registering with a slot formed longitudinally in one side of the casing adjacent its top wall, the pocket being formed for the removable reception of a lower record sheet and the adjustment of said sheet longitudinally of the casing relative to said inscription opening, longitudinally spaced spooling devices rotatably supported in the opposite ends of said drawer beyond the ends of said panels, said devices holding a record-receiving and inscription-transferring webbing, the intermediate portion of said webbing being movable over said upper panel and below the top wall of said casing, and means for removably clamping an upper record sheet on the upper surface of said top wall in longitudinally adjusted relationship with respect to said inscription opening.
6. In a manifolding register, an elongated casing having a top wall and a movable door-forming end wall, a drawer slidably positioned in said casing and movable into and out of the latter through the end of the casing containing said door wall, the top of said casing intermediately

11

of the length thereof being formed with an inscription opening, said drawer embodying a horizontally disposed upper plate arranged when the drawer is operatively positioned within the casing immediately below and in parallel relationship with the top wall of said casing, spooling devices carried by the opposite longitudinal ends of said drawer, said devices holding a record-receiving and inscription-transferring webbing with the intermediate portion of the webbing present between said rolls extending over said upper plate and beneath the top wall of said casing in registry with said inscription opening, a lower horizontally disposed plate formed with said drawer immediately beneath said upper plate and spaced from the latter to provide an open-sided pocket for the reception of a removable lower record sheet, the open side of said pocket registering with a slot formed longitudinally in one side of said casing adjacent the top thereof, 20 said pocket receiving for longitudinal movement therein a lower record card, said lower plate being formed intermediately of its length with a locally raised region projecting above the horizontal plane in which the major portion of the lower 25

10
5

12

plate lies, said locally raised region being disposed in registry with the inscription opening in said top wall and said guide plate, means carried by the top wall of said casing for removably clamping an upper record sheet in desired registry with said inscription opening, and manually operated means accessible from the exterior of said casing for operating said spooling devices to impart longitudinal movement to said webbing.

WILLIAM DALE WINDERS.
